DRUM TYPE HEAT EXCHANGER

Richard W. Kritzer, Chicago, Ill.
(% Peerless of America, 5830 N. Pulaski Road)

Filed June 14, 1956, Ser. No. 591,491

1 Claim. (Cl. 257—241)

The invention relates to a heat-exchanger of the drum-type which includes spirally coiled tubing and fins, and the fabrication thereof.

One object of the invention is to provide a heat-exchanger of this type which can be expeditiously and economically fabricated.

Another object of the invention is to provide an improved method of fabricating heat-exchangers of this type.

Other objects will appear from the detail description.

The invention consists in the many novel features hereinafter set forth and more particularly by the claim at the conclusion hereof.

In the drawings:

Fig. 1 is a plan view of an exchanger embodying the invention, the drum or casing being shown in section;

Fig. 2 is a section taken on line 2—2 of Fig. 1;

Fig. 3 is a perspective view of a portion of the fin-forming structure or strip;

Fig. 4 is a section on line 4—4 of Fig. 1; and

Fig. 5 is a section taken on line 5—5 of Fig. 1.

The invention is exemplified in a heat-exchange unit which comprises: a drum or casing which includes a sleeve or hub 10 and an annular jacket or drum 11; a series of three coils of tubing 12, 13 and 14, of cylindrical cross section, each including spiral convolutions in side-by-side relation and spaced apart radially. A header 16 is communicatively connected to the inner end of the coils adjacent sleeve 10 and a header 17 is communicatively connected to the outer ends of the coils for the circulation of a fluid, usually a refrigerant, through the coils, one of the headers serving as an inlet and the other as an outlet for the fluid. The radial spacings of the convolutions of the coils form a spiral passage between the convolutions of the coils for the flow of air longitudinally through the drum or casing. An air impeller (not illustrated) is usually mounted over the coils and driven by an electric motor which may be mounted in the sleeve 10 for forcing air to be cooled through the drum, as well understood in the art.

An elongated or continuous strip of fin-stock, such as thin sheet aluminum, is fabricated into a fin-structure, generally designated 15, which fits and is confined in the spiral space between the convolutions of the series of coils. This fin-structure is utilized to transfer heat from the fluid in the coils to the air which contacts said structure and the tubing. The fin-structure includes a series of substantially coplanar fin-sections 20 which are adapted to extend across or span the spiral space between the convolutions of the entire series of coils and integral ends 21 which are formed by bends which alternately connect opposite ends of contiguous sections 20 and function as seats for the coils of tubing. Each end 21 includes substantially flat portions 22 and curved portions 23 which conform to the cross-sectional contour of the tubing for closely fitting contact between the outer faces of ends 21 and the convolutions of the coils. Each fin-section 20 has an end 21 provided with seats for the outer per-

2

ipheral portions of one convolution of each of the spiral coils 12, 13 and 14, and an opposite end 21 provided with seats for the inner portions of the next convolutions of the coils, the strip forming the fin-structure being of

5 sufficient width for that purpose. The structure 20 before assembly with the coils is readily flexible into generally spiral contour to conform to the spiral convolutions of the coils, and, after said assembly, provides fins in the air stream between said convolutions. The tubing of the coils is bendable spirally around the fin-structure to produce pressure-contact between the seats on the ends 21 of the fin-structure and the contacting portions of the coils. The faces of sections 20 and inner faces of ends 21 are exposed to the air stream through the drum.

10 In shaping the strip of fin-stock into the continuous structure 15, and bending the metal in the ends 21 to form the seats for the tubing, the metal is ruptured as at 24, at the crests of the curved portions 23. This provides for flexibility in said curved portions to conform to the cross-sectional contour of the contiguous tubing, and also provides openings for the flow of air to the clearance between the coils which are in side-by-side relation.

A portion of the inner convolution of each of the coils 12, 13 and 14 extends around a portion of the sleeve 10 and thence spirally around to the adjoining end of the next convolution where the inner end of the fin-structure is located. A first elongated tapered baffle 30 closes the gap between sleeve 10 and the header 16 where said portion of the inner convolutions extend spirally away from the sleeve. This baffle extends to the fin-section 20 on the inner end of the spirally coiled fin-structure adjacent header 16. A portion of the outer convolution of each of said coils extends spirally around casing 11. A second elongated tubular baffle 31 closes the gap around said

25 portion and the casing 11 and extends circumferentially to the header 17 and the fin-section 20 on the outer end of the fin-structure. These baffles and construction confine the longitudinal air flow through casing to the spirally extending radial spaces between the convolutions of the

30 coils in which the fin-structure is disposed, for contacting the air with the fin-structure and efficiency in heat transfer.

In the fabrication of the unit, the fin-structure 15 is of sufficient length to extend between the spiral gaps between the convolutions of the coils between the headers 45 16 and 17. Before assembly, the fin-structure with the coils or casing is linear and readily bendable into spiral contour because the sections 20 are readily flexible between the ends 21. This facilitates the flexing of the strip 15 into spiral contour conformably to the coils of tubing. 50 In assembling the unit, the header 16 is fixedly held in the baffle 30 which is secured to the sleeve or hub 10. The tubing for the coils 12, 13 and 14 which is sufficiently bendable transversely for this purpose, is bent around the sleeve 10 and baffle 30 to progressively form the inner convolution of each of the coils. The fin-structure 15 is folded around the outer periphery of said inner convolutions. This bending of the tubing and folding of the fin-structure is progressively continued until the coils and fin-structure are entirely assembled in spirally wrapped relation.

The assembled fin-structure and coils 12, 13 and 14 are pressed together and contracted and while so contracted are inserted sidewise into the drum 11. This contraction secures the ends 21 of the fin-structure in the coils. The concave seats on the ends 21 of the fin-structure are interlocked against relative movement coaxially of the sleeve 10 and drum 11, with the header 16 adjacent baffle 30 and header 17 adjacent baffle 31. The inner ends of the coils are confined by a flange 40 70 on one end of sleeve 10 and a ring 41, and the other ends of the coils are confined and held in the drum be-

tween a flange 42 on the drum and a ring 43. The assembled coils and fin-structure are then secured together with pressure contact or in close-fitting relation for efficient heat-transfer from the fluid in the coils to the fin-structure. The air passing through the spiral gaps between the convolutions of the coils will contact the faces of the fins formed by sections 20, the inner faces of bends 21 and the exposed inner face portions of the coils between sections.

The invention exemplifies a heat-transfer element of the drum-type which is efficient in operation and simple in construction and an economical method of fabricating and assembling the unit.

The invention is not to be understood as limited to the details set forth, since these may be modified within the scope of the appended claim without departing from the spirit and scope of the invention.

Having thus described the invention what I claim as new and desire to secure by Letters Patent is:

A drum type heat exchange unit comprising in combination a drum casing including an open-ended tubular centrally disposed hub and an outer cylindrical casing shell concentric with the hub and spaced radially therefrom, a first tubular header disposed within said outer cylindrical casing shell and in close proximity to said tubular hub exteriorly of the latter, a second tubular header disposed within said outer cylindrical casing shell and in close proximity to the latter, the axes of said tubular headers extending parallel to the common axis of the tubular hub and cylindrical casing shell, a plurality of vertically spaced, superimposed, uniformly involute tubular coils of cylindrical cross section disposed within said drum casing between the hub and casing shell, the inner ends of said involute tubular coils communicating with the interior of said first tubular header and the outer ends of said involute tubular coils communicating with the interior of said second tubular header, the innermost convolutions of said involute coils being partially wrapped around said hub in contiguous relation to a major arcuate portion of the cylindrical surface thereof, the outermost convolutions of said involute coils closely hugging a major arcuate portion of

the inner cylindrical surface of the casing shell, a first elongated tapered baffle member filling the space existing between the innermost convolutions of said involute coils and the outer cylindrical surface of the tubular hub and

- 5 partially encompassing said first tubular header and the hub, a second elongated tubular baffle member filling the space existing between the outermost convolutions of said involute coils and the inner cylindrical surface of said casing shell, and a continuous strip of fin stock disposed between adjacent convolutions of the various involute coils and extending in involute fashion from said second baffle member to said first baffle member, said fin stock providing a multiplicity of closely spaced radially extending fin sections common to and bridging the distance between the adjacent convolutions of each involute coil, the adjacent inside edges of alternate pairs of adjacent fin sections being connected together by integral webs of full fin stock height, the adjacent outside edges of other alternate pairs of adjacent fin sections being connected together by integral webs of full fin stock height, each of said webs spanning said superimposed involute coils and being formed with imperforate curved seats in intimate face-to-face contact with the various coil convolutions, the material of each web between adjacent curved seats being ruptured to define openings through the web, and presenting curved fingers which closely hub the curved wall of the adjacent coil convolutions, thereby lending flexibility to said curved seats as well as affording intimate heat exchange between the 20 curved seats and the coil convolutions.
